UNITED STATES PATENT OFFICE.

SAM H. LIBBY, OF EAST ORANGE, NEW JERSEY, ASSIGNOR TO GENERAL ELECTRIC COMPANY, A CORPORATION OF NEW YORK.

SUSPENSION DEVICE FOR MONORAIL-CRANES.

1,077,726.

Specification of Letters Patent.

Patented Nov. 4, 1913.

Application filed October 12, 1912. Serial No. 725,509.

To all whom it may concern:

Be it known that I, SAM H. LIBBY, a citizen of the United States, residing at East Orange, county of Essex, State of New Jersey, have invented certain new and useful Improvements in Suspension Devices for Monorail-Cranes, of which the following is a specification.

This invention relates to overhead conveyers for freight of various kinds and its object is to facilitate the movement of such conveyer along the overhead rail from which it is suspended.

In my prior Patent, No. 1,022,033, dated April 2, 1912, I have shown a conveyer of the general type to which the present invention relates; that is to say, a frame supported at each end on trucks which run on the lower flanges of an I-beam forming the track. In order to negotiate curves in the track, the trucks are swiveled to the frame. But if the ordinary king bolt is used for this purpose, it soon wears out, and moreover it does not provide sufficient flexibility of movement in lateral directions.

My present invention therefore consists of a king bolt for each end of said frame, having a ball and socket connection with its truck, in order to give freedom of movement in rounding curves or passing over irregularities in the track.

The invention is illustrated in the accompanying drawing, in which—

Figure 1 is a side elevation of an overhead conveyer embodying my improvements, and Fig. 2 shows a portion of one of the trucks partly broken away to show the king bolt and its bearing in vertical section.

The overhead track is preferably an I-beam whose lower flanges support the wheels of the trucks 2. There are two trucks, one at each end of the frame 3. An electric motor 4 is geared to the driving wheels of each truck, current being conveyed to said motors in any suitable manner. An electric motor 5 is mounted in the frame 3 and its armature shaft is geared to a winding shaft 6 on which are secured two drums 7, from each of which depends a hoisting rope 8, preferably provided with a pulley block 9 and hook 10.

The ends of the frame 3 have projecting arms 11 through which pass the king bolts 12 by which said frame is suspended from the trucks 2. On the lower end of each bolt 55 is a nut 13, supporting a helical spring 14 on which the arm 11 rests. The head 15 of the bolt has a ball and socket bearing in the frame of the truck, preferably constructed as follows: The opening 16 through which the bolt passes is enough larger than said bolt to give it plenty of play. At the upper end of said opening an annular seat 17 is provided having a spherical concavity concentric with a point in the axis of the 65 head of the bolt. Resting on this seat is a convex spherical washer 18 on which hangs the head of the bolt. The upper side of the washer is preferably provided with an annular rib which fits into a groove in the underside of the head 15.

The weight of the frame 3 and its accessories and load compresses the spring 14 so that the arms 11 do not lie in contact with the frames of the trucks. When the 75 conveyer is moving along the track, the ball and socket suspension permits a free and universal movement of the truck with respect to the arm, so that in rounding curves or passing humps or hollows in the track 80 there will be no undue frictional strains upon the bolts, wear will be reduced to a minimum and less power will be required to drive the conveyer.

In accordance with the provisions of the 85 patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is:— 95

1. The combination with an overhead conveyer, comprising a frame suspended from two trucks, of a king bolt for each truck having a spherical washer under its head, and a spherical seat for said washer 100 in the frame of the truck.

2. An overhead conveyer comprising two

trucks, a frame located between said trucks and having an arm at each end, a king bolt passing through each arm and the frame of the corresponding truck, a ball and socket joint at the upper end of each bolt, a nut on its lower end, and a spring between said nut and the arm of the conveyer frame.

In witness whereof, I have hereunto set my hand this tenth day of October, 1912.

SAM H. LIBBY.
